CAR DOOR

Frank H. Rogers, Estancia, N. Mex.

Application August 30, 1943, Serial No. 500,569

5 Claims. (Cl. 16—99)

This invention relates to car doors and particularly has relation to a sliding door of a type used in connection with a box car wherein the lower portion of the door is provided with a freely mounted wheeled member for facilitating the shifting of the door from one position to another, and it is primarily an object of the invention to provide means whereby this wheeled member, when the door is in desired shifted position, is automatically raised and maintained in an operative position or free of contact with the trackway with which said wheeled member coacts and which furthermore assures the door having desired flat contact with the lower trackway.

The invention consists in the details of construction and in the combination and arrangement of the several parts of my improved car door whereby certain important advantages are attained, as will be hereinafter more fully set forth.

In order that my invention may be better understood, I will now proceed to describe the same with reference to the accompanying drawings, wherein:

Figure 1 is a fragmentary view in elevation illustrating a door constructed in accordance with an embodiment of the invention.

Figure 2 is a view partly in elevation and partly in section illustrating the details of construction.

Figure 3 is an enlarged sectional view taken substantially on the line 3—3 of Figure 2.

Figure 4 is an enlarged sectional view taken substantially on the line 4—4 of Figure 2.

Figure 5 is a view in perspective of the spring member herein employed unapplied.

Figure 6 is a fragmentary view partly in section and partly in elevation illustrating another embodiment of the invention.

Figure 7 is a detailed sectional view taken substantially on the line 7—7 of Figure 6.

Figure 8 is a view in perspective of the spring element employed, unapplied, and

Figure 9 is a fragmentary view partly in section and partly in elevation illustrating a still further embodiment of the invention.

In the embodiment of the invention as illustrated in Figure 1, W denotes the side wall of a box car or the like having the usual door opening with which is associated a sliding door D. Extending along the wall W immediately adjacent the lower end of the door opening 1 is a track T herein disclosed as having its upper or top face flat. This track T may be held in applied po-

sition in any manner preferred, it only being required that the upper portion of the track be slightly spaced, as illustrated in Figure 3, from the adjacent outer face of the wall W, so that the lower portion of the door D may straddle the track T.

The door D is of any desired construction but is preferably of a hollow type and this door D includes the horizontally disposed or bottom plate 10 2 positioned a desired distance inwardly of the lower edges of the walls 3 of the door D and which is adapted to have direct flat contact with the top 6 of the track T so that the door D under its own weight may be effectively held against sliding movement.

At predetermined points spaced therealong this plate 2 is provided with the longitudinally disposed slots 4 herein disclosed as two in number and through each of which is adapted to be disposed a roller 5. This roller 5 is rotatably carried by an elongated rigid member 6 of any desired structure or material which is freely positioned between the lower portions of the walls 3 of the door.

25 Disposed through the lower portion of the door D at substantially its longitudinal center and at a desired point above the applied member 6 is a shaft 7 which extends exteriorly of the door and said exterior or extended portion carries an operating member or handle 8. The shaft 7 between the walls 3 of the door D carries an outstanding cam member 9 which, upon swinging movement of the shaft 7 in one direction, forces the member 6 downwardly and the rollers 5 into contact with the track T through the openings and with a resultant raising of the door D so that it can be readily shifted as desired.

After the door D has been moved to desired position, the shaft 7 is rocked in a direction to raise the cam 7 with respect to the member 6, whereupon the member 6 is automatically lifted or raised to free the rollers 5 from contact with the track T to assure the plate 2 having effective flat contact with the track T to maintain the door D against sliding movement. This raising of the member 6 also prevents the flattening of the rollers 5 which would occur as the result of the shocks and jars incident to travel should such rollers 5 during such travel be allowed to have contact with the track T.

As illustrated, the means for automatically raising the member 6 comprises an elongated flat spring 10 having its central portion anchored, as at 11, to the central portion of the member 6. This spring 10 is above the member 6 and sub-

stantially centrally of the rollers 5 and the extremities of the spring 10 freely contact from above with the pins 12 or the like secured to and intersecting the walls 3 of the door D.

In the embodiment of the invention as illustrated in Figures 6 to 8 of the drawings, the sliding door S is provided with a bottom plate 14 for coaction with the bottom track B in the same manner as set forth with respect to the bottom plate 2. Within the lower portion of the door S is the rigid member 15 carrying the rollers 16 for contact from above with the track B.

The central portion of this member 15 has secured to the top face thereof the flat spring 17. This spring 17 has its central portion anchored, as at 18, to the member 15 and the extremities thereof freely contact from above the cross pins 19 secured to and intersecting the side walls 20 of the door 5. Within the lower portion of the door S and above the member 15 and spring 17 is a rock shaft 21.

This rock shaft 21 extends lengthwise of the door S and has one end portion extending beyond the inner end of the door and said extended portion carries an upstanding operating lever 22 for rocking the shaft to bring into contact from above with the member 15 the cam arms 23 to effect the desired raising of the door S for shifting movement along the track B.

In the form of the invention as illustrated in Figure 9, there is disclosed the use of a double cam 24 which is fixed for rocking movement with the shaft 25 which is mounted and operated in the same manner as hereinbefore set forth with respect to the shaft 7 as comprised in the first form of the invention. By the use of the double cam, the desired movement of the rigid member 26 is effected to bring the rollers (not shown) of the member 26 into proper engagement with the track upon throwing of the operating lever 27 in either direction. The extent of swinging movement of the lever 27 in either of such directions is limited by the suitably positioned stop lugs 28 carried by the car door C.

From the foregoing description it is thought to be obvious that a car door constructed in accordance with my invention is particularly well adapted for use by reason of the convenience and facility with which it may be assembled and operated.

What is claimed is:

1. A sliding door structure comprising a door body mounted to have movement longitudinally of a track and to have up and down movement with respect to the track, an elongated member extending lengthwise of and disposed adjacent to the bottom edge of the door, rollers carried by said member for contact with the track, an elongated flat spring disposed over and longitudinally of said member, said spring being secured

substantially centrally between its ends to the member and curving upwardly from its transverse center away from the member, means forming a loose connection between each end of the spring and the door body whereby the member and rollers are suspended spaced from the track, and means carried by the door for forcing the member downwardly to bring said rollers into working engagement with the track, said spring being flexed and placed under tension when the member is forced downwardly.

2. A structure as set forth in claim 1, in which the last means comprises a pivoted cam supported upon the door for contacting the top of the spring to flex the spring and force the member downwardly, when oscillated.

3. A door structure as set forth in claim 1, in which the last means comprises a shaft supported for rocking movement on an axis lying above and extending longitudinally of said member, means for rocking the shaft, and cams carried by the shaft for engaging the top of the member to force the member and rollers downwardly against the resistance of the spring when the shaft is rocked in one direction.

4. A door structure as set forth in claim 1, in which the loose connection forming means between the ends of the spring and the door comprises a guide eye formed at each end of the spring and a pin carried by the door and extending transversely through each eye.

5. A sliding door structure comprising a door body mounted to have movement longitudinally of a track and to have up and down movement with respect thereto, a bottom plate carried by the door for contact with the track to hold the door against shifting movement along the track, the portion of the door above said bottom plate being hollow, a straight rigid bar member disposed for free movement within the door above the bottom plate, said bottom plate being provided with openings, rollers carried by said member to extend out through the openings in the bottom plate of the door for contact with the track, means for exerting pressure on the member for bringing the rollers into contact with the track to raise the door, means independent of said pressure exerting means for automatically maintaining said member in a raised position when the last named means is inoperative, said member when in its raised position holding the wheels free of contact with the track, said means for raising the member comprising a flat spring, means anchoring the central portion of the spring to the member, the spring being formed at each end to provide a guide extending in a direction lengthwise thereof, and elements carried by the door and each freely engaged in one of said guides.

FRANK H. ROGERS.
